STANLEY FOSTER, OF PORTO BELLO, JAMAICA, BRITISH WEST INDIES.

TYPE-WRITER PAD.

1,290,159.

Specification of Letters Patent. Patented Jan. 7, 1919.

Application filed March 1, 1918. Serial No. 219,910.

To all whom it may concern:

Be it known that I, STANLEY FOSTER, a subject of the King of Great Britain, residing at Porto Bello, Montego Bay, Jamaica, 5 British West Indies, have invented certain new and useful Improvements in Type-Writer Pads, of which the following is a specification.

This invention relates to typewriters, and 10 more especially to the feet thereof which rest on the desk; and the object of the same is to produce pads for said feet which will not only cushion the blows of the operator's fingers but will deaden the noise produced 15 ordinarily in the act of writing.

My invention consists in a peculiar form 20 of pad which is an improvement over the ordinary rubber plug now commonly used at this point, and details will be found below

25 while reference is made to the accompanying drawings, in which:—

Figure 1 is a side elevation of a typewriter with these pads applied, and

Fig. 2 is an enlarged vertical central 25 sectional view of one of the pads.

The typewriter is only diagrammatically shown in Fig. 1 to illustrate the use of the invention. The latter consists of upper and lower rubber plugs 1 and 2, connected 30 by a coiled spring 3. The upper plug is attached to the foot of the typewriter and the lower plug rests on the desk top. Each plug comprises a disk-like body and an integral and reduced shank projecting from the body 35 toward the other plug, thereby leaving a shoulder 4 upon which rests one extreme coil 5 of the spring 3, and this coil or convolution is preferably made a little smaller than the remaining convolutions so that it will 40 grip the shank to prevent the parts of the device from becoming disconnected. The upper plug is tubular as shown and is provided with a hole through which the usual screw or other fastening device is passed up- 45 ward into the typewriter foot to hold the pad in place. Its tubular body is numbered 6, and the hole through its disk is numbered 7. The screw or fastening device need not be shown. Attention is invited to

50 the fact that the combined length of the two shanks is greater than the aggregate length of the spring when the latter is compressed with its coils or convolutions in contact with each other, the purpose of this detail being 55 explained below.

In the application of a set of pads of this

character to the feet of an ordinary typewriter, the screws or fastening devices are removed and the old plugs or pads discarded. The new plugs are now brought 60 into position, and the screws passed upward through the holes 7 into the feet or threaded sockets therein, so that the upper plugs are held against said feet with their shanks downward. Now the spiral springs 65 are screwed onto these shanks, their uppermost coils or convolutions 5 slightly embedding the rubber of the shank so that the springs will not fall off. Finally the lower plugs are screwed into the lower ends of the 70 springs, with the same result. The typewriter is now set onto the table or desk and its weight compresses the devices so that it is eventually distributed to the four springs 75 as will be clear.

Now when the operator writes, her blows on the keys are cushioned and the noise of writing is deadened as first above suggested. It is obvious that this effect is brought about by the combined use of two rubber plugs 80 and a coiled spring of metal, and that no metal part touches any other metal part. Not even may the convolutions of the spring touch each other, because of the fact that the two shanks aggregate a greater length than 85 the spring when compressed to its utmost, as will be seen by an examination of Fig. 2 of the drawings. While I have described this invention as applicable to the feet of a typewriter, it is obvious that it is not limited thus in its use. Therefore if we assume 90 that the machine to be carried by the structure is so heavy that the parts are compressed beyond the sustaining power of the spring, even only at times, the result would be merely 95 that the lower end of the upper shank would come in contact with the upper end of the lower shank, and the foot of the machine would be sustained by a two-part rubber plug which itself would yield, and meanwhile no metal parts would touch any metal parts and noise would be avoided.

What is claimed as new is:—

The herein described pad for the foot of a typewriter or like machine, the same comprising an upper rubber plug having a disk-like body and a hole through its center and a reduced tubular shank depending from and integral with said body, a lower rubber plug also having a disk-like body and a reduced shank integral with the same and projecting toward the other shank, and a heli- 105 110

cal spring connecting said plugs and touching them only, its endmost convolutions being smaller than the others and embedding the shanks of the plugs next their bodies, the
5 combined length of said shanks being greater than the aggregate length of the spring when compressed, for the purpose set forth.

In testimony whereof I affix my signature in presence of two witnesses.

STANLEY FOSTER.
